CLAIM

The ornamental design for a headband for head mount display, as shown and described.

DESCRIPTION

FIG. 1 is a perspective view of a headband for head mount display showing our new design;

FIG. 2 is another perspective view thereof;

FIG. 3 is still another perspective view thereof;

FIG. 4 is yet another perspective view thereof;

FIG. 5 is a front view thereof;

FIG. 6 is a rear view thereof;

FIG. 7 is a left side view thereof;

FIG. 8 is a right side view thereof;

FIG. 9 is a top view thereof;

FIG. 10 is a bottom view thereof;

FIG. 11 is a right side view thereof in a first usage state; and,

FIG. 12 is a right side view thereof in a second usage state. The broken lines in the drawings illustrate portions of the headband for head mount display and form no part of the claimed design. The broken lines shown in FIGS. 11-12 illustrate environment structures and form no part of the claimed design. In FIGS. 11-12, the cable extending from the front piece of the head mount display passes through the ring of the headband, and the length of the headband could be adjusted to adapt different head types of users.
